UNITED STATES PATENT OFFICE.

EDMUND BESELL WHALLEY, OF SHEFFIELD, ENGLAND.

MEANS FOR BARKING TIMBER.

Application filed June 24, 1921. Serial No. 480,137.

To all whom it may concern:

Be it known that I, EDMUND BESELL WHALLEY, of 3 Park Crescent, Sheffield, in the county of York, England, a subject of the King of Great Britain and Ireland, have invented a certain new and useful Means for Barking Timber, of which the following is a specification.

This invention relates to the barking of timber and has for its object to improve on the present methods of performing that operation which are often somewhat lengthy and are wasteful in timber and to that end this invention consists in a novel method by 10 which the bark is removed endwise or longitudinally (as distinct from the usual manner of removing it circumferentially); thus leaving, if desired, the surface of the timber perfectly smooth in its natural state, also 15 my invention includes a novel form of apparatus for carrying out the above named improved method of barking.

Apparatus made in accordance with this invention is characterized in that the bark 20 is removed longitudinally, the log or machine being given longitudinal movement with or without relative rotary movement.

According to one form of this invention, when barking a log, one end is first prepared, if necessary, by removing a ring of bark. This is sometimes done when the tree is felled or before it is brought to the barking machine. The end of the log is then 25 inserted endwise into a machine which has a series of radially disposed barking tools which collectively cover the whole circumference of the log, which latter is then given an endwise and if necessary rotary feeding movement through the ring or rings of tools, 30 or the machine may be moved longitudinally instead of the log. Each tool is capable of yielding in a radial direction so as to adapt itself to irregularities in the contour of the log and to obviate digging into the wood of the 35 log and so wasting valuable timber. By adjusting the tools or employing suitable ones, the surface of the wood can be removed if desired.

I will now describe one convenient form of 40 apparatus for barking by my improved method, but it should be understood that I do not confine myself to the particular construction so described.

Fig. 1, is an elevation of one form of device for removing a ring of bark from the 45 end of a log.

Fig. 2, is a side elevation of one form of machine for barking a log.

Fig. 3, is an end elevation of same.

Fig. 4, is an end view of one ring of tools 50 showing a rotary annular device for drawing the tools outwards simultaneously.

Fig. 5 is an elevation of one form of tool adapted for use with apparatus made in accordance with this invention; and 55

Fig. 6 is a plan view thereof.

A log to be barked is placed upon a log spinner of the usual character, i. e. two rollers *a*, *a*, mounted on a suitable frame and adapted to be rotated in the same direction, 70 the log *b*, resting between them and in consequence rotated in the opposite direction. An end peeling device is then applied to the log *b*, which device consists of a pivoted lever *c*, (hereinafter referred to as the main lever) 75 on which are freely mounted two wheels *d*, *d*, arranged in tandem fashion. These wheels are caused to bear upon the revolving log *b*. Pivoted to the main lever *c*, is a second lever *e*, which is provided with a 80 knife edge wheel *f*, which runs in advance of a peeling chisel *g*, also secured to the second lever. The knife edge wheel cuts the bark circumferentially and the chisel pares off a 85 strip equal to its own width. If the end of a log should be free from bark it will of course be obvious that this preliminary operation is entirely unnecessary.

When the end of the log has been so prepared it is ready for the barking machine 90 and this consists of suitable standards, bed and framing *h*, supporting an annular headstock, or headstocks *j*, *j*, in which are arranged radially disposed rings of chisels or paring tools *k*, *k*, *k*. These rings of tools 95 are preferably arranged in series and each tool engages different portions of the circumference of the log, so that collectively they cover the entire circumference. Each chisel or tool is preferably mounted in a 100 guide *m*, as shown in Fig. 4, and is pressed up to its work by a coiled spring *n*, either in compression as shown or in tension, or by any other suitable device. With such an arrangement each chisel is capable of yielding 105 and so adapts itself to variations in the contour of the log.

The logs may be supported on rollers *o*, *p*, and given a longitudinal and if necessary, rotary motion by any suitable means and at 110 any desired speed. These rollers may if desired be supported on springs so as to yield

to any variations in the contour of the logs and thus allow of a more or less smooth horizontal movement.

In use the barked or reduced end of a log 5 is first inserted into the machine, the tools bearing against the barked surface of the log, said log is given a longitudinal motion and the tools pare off the bark longitudinally.

10 One very convenient form of chisel or tool to employ is one of square section as shown in Figs. 5 and 6 and having four cutting edges k^1, k^2, k^3, k^4 , (one on each face) so that when one edge becomes blunted, another can 15 be brought into operation by simply turning the tool. The tools may be disposed at right angles to the longitudinal axis of the log or at any suitable angle thereto and have a square end face k^5 to bear on the 20 face of the log without cutting the wood of the log.

Provision is made for drawing the tools outwardly simultaneously when desired and this may be effected by a rotary annular device 25 consisting of a plate q provided with a series of cam faces r, r , to engage pins s, s , or projections on the outer ends of the chisels or tools and rollers t, t , may be provided on said pins. This plate may be operated by levers v, v , against the action of a spring w , so that when said plate is given a turn the chisels are simultaneously drawn outward by the action of the rollers t, t , climbing the cam faces r, r . It will thus be 30 seen that various sized logs (within reasonable limits) may be barked in one machine.

What I claim and desire to secure by Letters Patent is:—

1. In a machine for barking timber, tools 40 mounted radially with respect to a log, means independent of the log for simultaneously moving said tools towards and away from the longitudinal axis of the machine, said tools being provided with a plurality of cutting edges and an end surface adapted to bear and ride on the surface of the log without cutting into said surface of the log, and means for rotating the tools on their axes to bring a new cutting edge into operation.

2. In a machine for barking timber, tools mounted radially with respect to the log, and means independent of the log for moving said tools independently of one another and 55 simultaneously towards and away from the longitudinal axis of the machine.

3. In a machine for barking timber, tools mounted radially with respect to the log, means independent of the log for moving said tools radially independently of one another and simultaneously towards and away from the longitudinal axis of the machine, said tools being provided with a plurality of cutting edges and an end surface adapted to bear and ride on the surface of the log 60 without cutting into said surface of the log, and means for rotating the tools on their axes to bring a new cutting edge into operation.

4. In a machine for barking timber, tools 70 mounted radially with respect to the log, means independent of the log for simultaneously moving said tools radially towards and away from the longitudinal axis of the machine, said means for moving the tools comprising a plate and a plurality of inclined surfaces on the plate adapted to engage rollers mounted on the tool shafts.

5. In a machine for barking timber, tools mounted radially with respect to the log, 80 means independent of the log for simultaneously moving said tools radially towards and away from the longitudinal axis of the machine, said tools being provided with a plurality of cutting edges and an end surface adapted to bear and ride on the surface of the log without cutting into said surface of the log, and means for rotating the tools on their axes to bring a new cutting edge into operation, said means for moving 85 the tools simultaneously comprising a plate and a plurality of inclined surfaces on said plate adapted to engage rollers mounted on the tool shafts.

6. A machine for barking timber comprising 95 a bed, an annular headstock on the bed, tools radially disposed on the headstock, means for permitting the tools to yield to the variations of the contour of a log, means for moving the log longitudinally, means 100 for simultaneously moving said tools towards and away from the surface of the log, said tools being provided with a plurality of cutting edges and an end surface adapted to bear and ride on the surface of the log 105 without cutting into said surface of the log, and means for rotating the tools on their axes to bring a new cutting edge into operation.

In testimony whereof I have signed my 110 name to this specification.

EDMUND BESSELL WHALLEY.
